PROTECTION OF THE WALLS OF GASIFYING APPARATUS

Géza Szikla and Arthur Rozinek, Budapest,
HungaryApplication July 30, 1938, Serial No. 222,292
In Germany August 9, 1937

8 Claims. (CL 48—76)

The continued development of the apparatus for the gasification of fuel in a floating condition according to our Patent No. 2,099,968 led to the use of higher and higher temperatures in the 5 gasifying chamber in order to promote in an efficient manner the separation of the slag in a liquid condition.

The high temperature—together with the effects of the liquid slag—results, however, in an 10 inadmissibly great wear and tear of the refractory lining.

The present invention eliminates this drawback. Utilizing the particular conditions existing in the gasifying chamber, it eliminates in the 15 most simple manner any disadvantageous wear and tear of the walls; at the same time it enables very favourable conditions to be created for the gasification of the fine-grained coke.

In accordance with the invention, tubes are 20 arranged and spaced so that a backing of coke (coke wall) and/or of a mixture of coal and coke, with an admixture of slag, is collected at the natural angle or slope in such a manner, that jointly with the supporting tubes a wall or boundary of the furnace and/or gasifying chamber is formed.

The invention is of course not confined to the 25 gasifying apparatus for the gasification of fuel in a floating condition, according to our previous 30 patents; on the contrary the coke wall according to the present invention can be employed in connection with all gasifying chambers in which fine-grained fuel is gasified whilst being entirely or partly in a floating condition with a restricted 35 supply of air and in which temperatures above the melting point of the slag prevail.

The invention is based on the following considerations and recognition of facts:

(1) Coke will resist the temperatures with 40 which it is necessary to deal in such cases, it will not melt and will not bake together.

(2) The admixture even of small quantities of coke dust will substantially increase the melting point of the mixture. Coke contents exceeding 45 20% of the ash will prevent the melting of the latter.

(3) The accumulation of coke having a grain size of e. g. up to 5 mm. in the combustion chamber, for instance on a shoulder, following the 50 natural angle of repose of the material, will due to the heat radiation to which it is exposed have on its surface a temperature approximately equal to the temperature of the chamber. On the other hand, the hot gases diffusing into the deposit of 55 granules will in consequence of the heat-absorb-

ing chemical change undergone by them, be rapidly and efficiently cooled, the CO₂ being reduced by the coke to CO. Even if any free oxygen should possibly still be contained in the gas, such oxygen will effect the combustion of the coke 5 on the surface layer and will increase the temperature in this layer, but below the surface the cooling-down mentioned above of the gas will still take place.

These considerations are based on fine-grained 10 coke, seeing that the fresh coal introduced will at the high temperatures prevailing become converted into coke within a very short time. All that is necessary is to make provision for ensuring that in the case of coal of a baking kind this 15 coal should be converted into coke in individual granules, which will be the case in the gasifying apparatus for the gasification of fuel in a floating condition according to our prior patents as otherwise the small coal would bake together into 20 lumps of coke. Coke dust itself will in the case of all kinds of coal behave in the same favourable manner in the sense of the present invention.

The invention results from the further development of the fundamental idea disclosed in our 25 Patent No. 1,869,949 according to which an "inverted flame" develops in the interior of the crater of coke and ash which latter resists the highest temperatures as well as all detrimental influences of the liquid slag.

According to the invention this deposit of coke and ash is extended in the vertical direction so as to extend over the whole height of the gasifying chamber. This being done by arranging a 30 number of tubes above each other in such a manner as to ensure that fuel deposits are formed on or between the said tubes, in a manner corresponding to the natural angle of repose of the particular mixture of coke and slag. The tubes and the coke slope will build up to a wall in a 35 40 form resembling that of shutters. In order to increase the length of the slope, the tubes are fitted with fin-shaped extensions or two or more tubes are arranged so as to be in mutual contact. In the case of the gasifying equipment according to 45 our Patent No. 2,099,968 mentioned above there will thus be formed behind the supporting group of tubes a backing of coke and slag which will 50 permanently become supplemented from above by the particles of coke and slag continuously becoming deposited from the floating condition. It is however also possible to make provision for the said backing becoming continuously supplemented from the upper end of the row of tubes.

In what follows, the invention will be described 55

with reference to Fig. 1 in which a gasifying equipment, approximately corresponding to our Patent No. 2,099,968, is assumed by way of example. Fine-grained coal 10 is introduced in a known manner by means of the centrifugal catapult apparatus 7 into the de-gassing chamber II, for instance, in such a way that the fine-grained coal accumulates in piles 14 on the cascade levels composed of tubes 13 from which it drops. During its downward movement, it is de-gassed and coked by the contact with the hot gases. The fine-grained coke is accumulated in the mold 15 from which it is pulled by the stoker 16, moving in alternating directions, through the opening 17 and is conducted in this way in the path of the gas stream rising upwards in the direction of arrow 11 through the bottom opening 19 regulated by the slide 18.

In chamber I the coke is gasified in a floating condition by means of the air entering from below. The gases pass then in the direction of arrow 20 to their further utilization.

In the gasifying chamber I supporting tubes 2 are provided which are preferably equipped with fins 3. Between each tube 2 and the next one a fuel deposit 12 will be formed in accordance with the angle of repose 4 of the backing material (which latter may possibly be filled-in when setting the apparatus to work for the first time). These fuel deposits constitute, together with the tubes 2, the boundary walls 5. The particles of coke and slag floating about in the chamber II will partly drop behind the tubes onto the slope and will continuously make up for any diminution of the backing material.

It is, however, also possible to provide a construction in which the backing material is supplemented by the necessary supplementary quantities flowing down from above, as indicated for instance at 6. The material received here from the centrifugal catapult apparatus 7 will in accordance with the progress of the disappearance of the backing subside downwards. Naturally, the material deposited is in this case coal, which is converted into coke only during its downward progress.

From what has been said above the method of operation of the apparatus is self-explanatory. Inside these walls 5, 5 constituted by piles of coke and slag dammed up between tubes, even the highest temperatures are innocuous, and the liquid slag can not exert any disadvantageous effects whatever. In case it is only the products CO_2 and CO of the pure gasification of coke which, in addition to N_2 , are present inside the gasifying chamber I, the gas diffusing into the layer of coke and slag will due to the heat-absorbing decomposition of CO_2 when entering into reaction with C exert a strong cooling effect and at the same time an incineration will take place on the surface. The same process will take place in case the gas should moreover possibly also contain a certain quantity of O_2 , in which case this oxygen will effect the combustion of the incandescent coke on the surface, whilst the CO_2 part of the gas will in the deeper layers again immediately enter into a heat-absorbing reaction with C and become converted into CO . In both cases the gas penetrating into the interior of the coke and slag layer will exert a substantial cooling effect and will effect the chilling of the layer of coke.

In view of the fact that the gasification in this apparatus takes place in the presence of an insufficient amount of air, it will never be possible

that the incandescent coke should be completely consumed and that only ash should remain as a backing material. What really happens is that the granules of coke floating and tripping about in the chamber will continue to drop on the pile and prevent any accumulation of ash. Pure ash as a backing material has already been proposed by other inventors, notably in connection with combustion in the presence of an excessive quantity of air, in which case only pure ash, due to the given conditions, would result, but experience shows that at the high temperatures in question the ash would melt and flow away so that it would not be possible for any backing to be formed and, accordingly, any formation of a bordering wall for the gas would not be possible.

Accordingly it is a fundamental condition that the gasifying chamber to be equipped with the apparatus according to the present invention should be of the kind claimed in our Patent No. 2,099,968 in which fine-grained coke is gasified in a floating condition in the presence of an insufficient quantity of air.

It is only on the surface of the coke piles that any ash or slag will be formed, which at the high temperature prevailing will become molten, whilst after its penetration into the layer of coke it will in consequence of its cooling-down assume a pasty condition, and will accordingly wet the granules of coke and agglomerate them into lumps, in consequence whereof a pasty compound will be formed. Due to its pasty condition this mixture of coke and slag will present a greater angle of repose than if the backing were constituted merely of granules of coke capable of free flow. This will have favourable effects inasmuch as the angle of repose of this pasty mixture is substantially steeper. The normal angle of repose of dry coke in a state of incandescence amounts to about 45° , as against which this pasty mixture of coke and slag may be held firm under a steeper angle of e. g. 50° and even 60° . The angle of repose finally resulting for practical construction will be different according to the quantity and melting point of the slag contained in the mixture and according to the magnitude of the temperature in the gasifying pit.

The spacing of the tubes supporting the slope of coke and slag depends in the case of the same tube diameter on the factors enumerated below. The number of supporting tubes will be lower,

(1) The steeper the angle of repose,
(2) The more the angle of inclination of the surface laid through the tube centre line approximates the angle of slope of the backing material and

(3) The greater the length of the fines.

The serviceable slope is, as experiments have proven, in general 45° . If the coke becomes pasty on account of the fluidity of the slag, it may be 55° .

The mixture of coke and slag forming the backing represents a heat insulation of a very high-grade kind, due to the fact that it includes an ample quantity of finely divided gas. The heat conductivity of the insulation is substantially lower than that of firebricks or other refractory linings and approximates that of asbestos or spun glass.

Moreover, however, a fundamental condition of good insulation also consists in the presence of granules of coke by which the structure is held firm. Slag alone would become molten into a compound. Even if this compound should keep

firm and should not drip off it would by far not possess the heat-insulating effect of the porous backing of coke. Moreover, due to the action of gases on the coke, a rapid chilling will take place in the inner layers so that the heat losses on the external wall will be insignificant. Accordingly, the thickness of the backing can be kept at a very low figure. The external boundary may consist of ordinary brickwork or possibly of a metal shell.

10 It is also possible for the structure of the tube wall to be vertical or overhanging. A vertical arrangement is shown by the tubes 8 placed in such a manner that each pair of tubes will be in immediate contact. At the same time it is shown in connection herewith that between two rows of supporting tubes, which in this case consist of the tubes 2 and 8, it is possible to form a separating wall for instance in such a manner that from the centrifugal catapult apparatus 7 fine-grained coal is fed also at 10 between these two rows of tubes. Accordingly there exists in this case a backing between two rows of tubes. It should be added that it would be possible to 20 employ such a backing on any desired other parts of gasifying equipments also, e. g. as a baffle wall, a wall for the reflection of radiation, etc.

An overhanging arrangement of tubes placed at close mutual distances is represented at 9 below 30 the admission of fine-grained coal at 6. In the case of this overhanging arrangement it may be necessary, as a particular case, that the tubes should be placed as indicated, not only close to each other, but in immediately mutual contact, seeing that it is not possible for any slope of coke 35 to be formed between the tubes. This arrangement also, however, is applicable to a backing with the mixture of slag and coke or coal.

Double tubes, like the tubes 8 can be arranged 40 in lieu of the fin tubes, as described above. It is, however, also possible to manage with single tubes not fitted with any fins, if provision is made for these tubes being so arranged relative to each other as to ensure that with due regard to 45 the angle of repose an unbroken backing should become formed. This is indicated in Fig. 2 in which a sloping wall has been assumed and in which the central plane of the supporting tubes presents a slope resulting by paying due attention to the angle of repose 4.

50 What we claim is:

1. In an apparatus of the character described having a gasifying chamber in which gasification of floating fuel is effected in the presence of a 55 restricted quantity of air, said chamber being provided with walls each comprising a series of substantially horizontal tubes spaced apart one above the other, a retaining wall spaced from the series of tubes, and a filling of a high melting point mixture of coke and ash between said 60 series of tubes and retaining wall, said tubes being spaced apart a distance depending on the angle of repose of the mixture and the inclination of the series of tubes relative to the vertical.

65 2. An apparatus according to claim 1, in which the tubes are spaced apart in an askew direction, the slope of which giving the desired slope of the composite wall.

3. In an apparatus of the character described 70 having a gasifying chamber in which gasification of floating fuel is effected in the presence of a restricted quantity of air, said chamber being provided with walls each comprising a series of substantially horizontal tubes spaced apart one 75 above the other, a retaining wall spaced from

the series of tubes, a filling of a high melting point mixture of coke and ash between said series of tubes and retaining wall, said tubes being spaced apart a distance depending on the angle of repose of the mixture and the inclination of 5 the series of tubes relative to the vertical, and radial fins extending longitudinally of the tubes and projecting radially from the tubes substantially perpendicularly to the exposed surface of the filling between tubes to enable the spacing 10 between the tubes of the series to be increased.

4. An apparatus of the character described, comprising a large chamber confined within refractory walls having an air inlet in the bottom thereof and an outlet in one of said walls near 15 the bottom, means below the top of said chamber for feeding fuel into the upper portion of said chamber, a series of horizontal tubes extending across said chamber between the air inlet and said outlet, said series of tubes being spaced one 20 above the other and extending from said bottom upwardly to a point above said outlet and terminating below said fuel feeding means, a second series of similarly spaced and arranged tubes positioned between the first-recited series and the 25 outlet, a third series of similarly spaced and arranged tubes positioned between the air inlet and a wall of the chamber, a loose filling of coke and ash between the first and second series of tubes, and a loose filling of coke and ash between 30 the third series of tubes and the adjacent chamber wall, said first and third series of tubes defining between them a gasifying chamber.

5. An apparatus of the character described, comprising a large chamber confined within refractory walls having an air inlet in the bottom thereof and an outlet in one of said walls near 35 the bottom, means below the top of said chamber for feeding fuel into the upper portion of said chamber, a series of horizontal tubes extending across said chamber between the air inlet and said outlet, said series of tubes being spaced one above the other and extending from said bottom upwardly to a point above said outlet and terminating below said fuel feeding means, 40 a second series of similarly spaced and arranged tubes positioned between the first-recited series and the outlet, a third series of similarly spaced and arranged tubes positioned between the air inlet and a wall of the chamber, a loose filling of coke and ash between the first and second series of tubes, a loose filling of coke and ash between 45 the third series of tubes and the adjacent chamber wall, said first and third series of tubes defining between them a gasifying chamber, and means associated with each tube and extending into the filling in contact therewith for preventing the outflow of the filling between said tubes. 50

6. An apparatus of the character described, comprising a large chamber confined within refractory walls having an air inlet in the bottom thereof and an outlet in one of said walls near 55 the bottom, means below the top of said chamber for feeding fuel into the upper portion of said chamber, a series of horizontal tubes extending across said chamber between the air inlet and said outlet, said series of tubes being spaced one above the other and extending from said bottom upwardly to a point above said outlet and terminating below said fuel feeding means, a second 60 series of similarly spaced and arranged tubes positioned between the first-recited series and the outlet, a third series of similarly spaced and arranged tubes positioned between the air inlet and a wall of the chamber, a loose filling of coke 65 and ash between the third series of tubes and the adjacent chamber wall, said first and third series of tubes defining between them a gasifying chamber.

70

75

- and ash between the first and second series of tubes, a loose filling of coke and ash between the third series of tubes and the adjacent chamber wall, said first and third series of tubes defining between them a gasifying chamber, and a fin extending downwardly and inwardly from each tube into the filling in contact therewith for preventing the outflow of the filling between said tubes.
7. An apparatus of the character described, comprising a large chamber confined within refractory walls having an air inlet in the bottom thereof and an outlet in one of said walls near the bottom, means below the top of said chamber for feeding fuel into the upper portion of said chamber, a series of horizontal tubes extending across said chamber between the air inlet and said outlet, said series of tubes being spaced one above the other and extending from said bottom upwardly to a point above said outlet and terminating below said fuel feeding means, a second series of similarly spaced and arranged tubes positioned between the first-recited series and the outlet, a third series of similarly spaced and arranged tubes positioned between the air inlet and a wall of the chamber, a loose filling of coke and ash between the first and second series of tubes, a loose filling of coke and ash between the third series of tubes and the adjacent chamber wall, said first and third series of tubes defining between them a gasifying chamber, and a tube positioned alongside of each tube of the

series below and inwardly thereof so as to extend into the filling for preventing the outflow of the filling between tubes of the series.

8. An apparatus of the character described, comprising a large chamber confined within refractory walls having an air inlet in the bottom thereof and an outlet in one of said walls near the bottom, means below the top of said chamber for feeding fuel into the upper portion of said chamber, a series of horizontal tubes extending across said chamber between the air inlet and said outlet, said series of tubes being spaced one above the other and extending from said bottom upwardly to a point above said outlet and terminating below said fuel feeding means, wall 5 10 defining means extending across said chamber spaced from and substantially parallel to said series of tubes, said wall defining means being located between said series of tubes and the chamber outlet, a loose filling of coke and ash 15 between said series of tubes and the wall defining means, another series of similarly spaced and arranged tubes positioned between the air inlet of said chamber and an adjacent parallel wall of said chamber, and a loose filling of coke and 20 ash between said second recited series of tubes and the adjacent parallel wall of the chamber, the two series of tubes defining between them a 25 gasifying chamber.
